WEB FEEDING MECHANISM

Abraham Novick, Flushing, N. Y., assignor to F. L. Smith Machine Co. Inc., New York, N. Y., a corporation of New York

Application March 24, 1954, Serial No. 418,440

9 Claims. (Cl. 242—68)

This invention relates to web feeding mechanism, and more particularly to mechanism controlling the fixed position of the paper reel rotatably supported upon a reel shaft so that the ends of the reel will lie accurately in planes at right angles to the reel axis. Such mechanism is particularly useful in machines for cutting rhombic envelope blanks from web material and for automatically converting such blanks into envelopes. For illustrative purposes the invention is disclosed herein as embodied in a machine of the kind illustratively shown in Figs. 1 to 29 of my pending application, Serial No. 344,572, filed March 25, 1953, for Web Feed Envelope Machines.

In that machine, each blank when cut is required to have its shorter diagonal in coincidence with the prescribed central feed line. A flying cutter, adjustable about a vertical pivot, and also adjustable bodily in the direction of web feed, is provided, the first adjustment being designed to cause the line of cut to make a desired oblique angle with the prescribed central feed line of the cut blanks. A web supply frame carries a reel from which paper is advanced at different selected rates of feed to the flying cutter so that different lengths of web may be fed and cut as desired for making envelopes of different sizes.

It is important that the blanks form the true rhombic blanks because notching, trimming, gumming and folding operations which are mechanically performed upon the blanks are all performed on the assumption that the blanks are truly rhombic and are truly centered with reference to the prescribed feed line, and poor quality or defective results will be produced if the blanks are not true. The machine of this invention is provided with means to insure feeding of the web from a reel with its side edges travelling in prescribed paths.

In former machines no account has been taken of the fact that the core on which the paper reel is wound may be distorted or warped during shipment and storage so that when the core is mounted on the reel shaft, the ends of the reel do not lie accurately in planes at right angles to the reel axis and the plane in which the web is fed. When such irregularities are present the web feeding zone shifts laterally, causing the cut blanks to be imperfect.

It is a primary object of the present invention to provide means for correcting distortion or warping of the core on which the paper reel is wound insuring that the ends of the reel will lie accurately in parallel planes at right angles to the reel axis.

To this end, it is a feature that the core on which the reel paper is wound is mounted with a capacity for shifting or adjusting relative to the reel supporting shaft to correct for warping and distorting of the core of the reel.

Other objects and advantages will hereinafter appear. In the drawing, forming a part of this specification,

Figure 1 is a transverse, vertical sectional view, taken on line 1—1 of Fig. 2, showing the mechanism for mounting the core on which the paper reel is wound on the reel shaft;

Figure 2 is a vertical sectional view, taken on line 2—2 of Fig. 1, showing the web supplying parts of an illustrative machine embodying the present invention;

Figure 3 is an inner end elevational view of the right hand core supporting cone, looking towards the left end of Fig. 1;

Figure 4 is an inner end elevational view of the hub which supports the cone of Fig. 3;

2

Figure 5 is an end elevational view of the clamp plate associated with the cone and hub of Figs. 3 and 4; and

Figure 6 is an inner end elevational view of the left hand core-supporting cone of Fig. 1.

The illustrative machine includes a main frame 9, and mechanism carried by it designed to feed a web 10 to and through a flying cutter, not shown, consisting of a stationary knife and a rotary knife, the latter carried by a roller mounted on a shaft. This flying cutter is adjustable to produce lines of cut at various angles oblique to the direction of travel of the web 10.

The frame 9 includes extensions 11 (Fig. 2) in which bearing rollers 12 are mounted for rotatably supporting a reel shaft 13. The shaft 13 supports in a stationary position a core 14 upon which a paper reel 15 is wound. The web 10 is led upward from the reel past guide rollers 16 and 17 (Fig. 2) and then between stationary feed rollers 18 and 19.

In the practice of the present invention, means are provided for correcting inaccuracies due to the distortion or warping of the core 14 so that the ends of the reel 15 will lie accurately in planes at right angles to the reel axis and include a cylindrical hub 20 secured to the reel shaft 13 by a set screw 21, the hub 20 at the end thereof remote from screws 21 being integrally formed with a circular flange plate 22 and a four sided extension 23. As shown in Figs. 1 and 4, the plate 22 and extension 23 are provided with the central bore 24 aligned with the central bore of the hub and receive therethrough the reel shaft 13.

As shown in Figs. 1 and 3, a core-supporting cone 25 is integrally formed with a circular base 26 having a central opening 27 receiving therethrough in freely spaced relationship the reel shaft 13 and the extension 23 of hub 20 with the outer face of the base 26 lying flush with the inner face of the flange plate 22. The base plate 26 is provided with four equi-radially spaced circular openings 28 aligned with corresponding openings 29 provided in the flange plate 22, the diameter of the openings 29 being greater than that of the openings 28 for a purpose which will hereinafter become clear.

As a means of securing the core-supporting cone 25 to the flange plate 22 a circular clamp plate 30 is provided with a central circular opening 31 which receives therethrough in freely spaced relationship the hub 20 with the inner face of the clamp plate 30 lying flush with the outer face of the flange plate 22. The plate 30 is provided with four equi-radially spaced openings 33 aligned with the openings 28 in plate 26. The openings 28 in the base plate 26 are internally threaded and have screwed therein bolts 32 passing through the four equi-radially spaced openings 33 in plate 30 and the openings 29 in the flange plate 22, the heads 34 of the bolts engaging the clamp plate 30 on the outer face thereof, as will be obvious. It will be noted that the openings 29 in the flange plate 22 being of greater diameter than the bolts 32 will permit the vertical displacement of the latter and thereby the core supporting cone 25 in a manner which will hereinafter become more clear.

As shown in Figs. 1 and 3, the base plate 26 around its periphery is provided with four equi-radially spaced, inwardly extending internally threaded openings 35 which communicate with the central opening 27 by means of reduced, smooth bores 36, the bores 35, 36 being displaced radially forty-five degrees from the openings 28. Set screws 37 having reduced shanks 38 which extend into the bores 36 are screwed into each of the internally threaded bores 35. It will be noted that the length of the set screws 37 is slightly less than the length of the bores 35 and that the reduced shanks 38 are slightly greater in length than the length of the reduced bores 36. Thus, when the outer end of the set screws 37 coincide with the outer ends of the bores 35, the reduced shanks 38 extend through the inner ends of the bores 36 into contact with the extension 23 and support the cone 25 thereon.

With the right hand assembly just described in assembled position on the right hand end of the reel shaft 13, the core 14 having a bevelled inner end 39 is slid onto the cone 25.

The portion of the reel shaft 13, extending through the other reel supporting member 40 is, externally thread-

ed, as at 41, and has screwed thereon an internally threaded hub 42 integrally formed with a circular base plate 43 (Figs. 1 and 5), the base plate 43 being provided with oppositely disposed pairs of openings 44 adapted to receive therein the opposite ends of a spanner wrench or the like whereby to tighten the hub 42 on shaft 13. The inner face of the base plate 43 is integrally formed with a hollow cone 45 similar in size and shape to the cone 25 and supports thereon the other end of the core 14.

With the reel mounted on the reel shaft as shown in Fig. 1, the ends of the reel 15 may be then brought accurately into common planes at right angles to the reel axis by adjustment of any or all of the set screws 37, to correct for any distortion or warping of the core 14 prior to the starting of the machine.

To remove the core 14 after the paper reel 15 wound thereon has been completely cut, it is only necessary to unscrew the left hand supporting cone 45 which permits the removal of the core 14 from the cone 25 and shaft 13.

While various changes may be made in the detail construction, it shall be understood that such changes shall be within the spirit and scope of the present invention as defined by the appended claims.

What is claimed is:

1. A device for mounting a core upon a shaft comprising a hub secured to the shaft, a plate having a central opening surrounding said hub in freely spaced relationship thereto, means on the inner face of said plate for supporting one end of the core, means for mounting said plate on said hub adapted to permit transverse movement of said plate relative to said hub, means for adjusting the transverse position of said plate relative to said hub, and means for supporting the other end of the core.

2. A device for supporting a core upon a shaft comprising a hub secured to the shaft, a flange plate secured to said hub, a base plate having a central opening receiving said hub therethrough in freely spaced relationship, means for securing said flange plate and base plate together against longitudinal displacement therebetween while permitting transverse displacement of said base plate relative to said flange plate, means for effecting said transverse displacement, means on the inner face of said base plate for supporting one end of the core and means for supporting the other end of the core.

3. A device for supporting a core upon a shaft comprising a hub secured to the shaft, a flange plate secured to said hub intermediate the ends thereof, a base plate having a central opening receiving said hub therethrough in freely spaced relationship, a clamp plate on the outer face of said flange plate, said clamp plate having a central opening receiving said hub therethrough in freely spaced relationship, said clamp plate, flange plate and base plate having a plurality of radially spaced, aligned openings, said openings within said flange plate being of greater diameter than said openings within said clamp and base plates, fastening means within said aligned openings for securing said clamp, flange and base plates together, said base plate around its periphery having a plurality of inwardly extending, radially spaced, internally threaded openings communicating with said hub, set screw means within each of said internally threaded openings bearing on said hub, means on the inner face of said base plate for supporting one end of the core and means for supporting the other end of the core.

4. A device for supporting a core upon a shaft comprising a hub secured to the shaft, a flange plate secured to said hub intermediate the ends thereof, a base plate on the inner face of said flange plate having a central opening receiving said hub therethrough in freely spaced relationship, a clamp plate on the outer face of said flange plate and having a central opening receiving said hub therethrough in freely spaced relationship, said flange, base and clamp plates having radially spaced, aligned openings, said openings in said flange plate being of greater diameter than said openings in said base and clamp plates, said base plate openings being internally threaded, bolts within each of said aligned openings having enlarged heads engaging said clamp plate, said base plate around the periphery thereof having a plurality of inwardly extending, radially spaced, internally threaded openings communicating with said hub, set-screw means within each of said internally threaded openings bearing on said hub, means on the inner face of said base plate for supporting one end of the core and means for supporting the other end of the core.

5. A device for supporting a core upon a shaft comprising a hub secured to the shaft, a flange plate secured to the inner end of said hub, an angular extension on the inner face of said flange plate, a base plate having a central opening receiving said extension therethrough in freely spaced relationship and lying flush with the inner face of said flange plate, a clamp plate having a central opening receiving said hub therethrough in freely spaced relationship and lying flush with the outer face of said flange plate, said flange, base and clamp plates having radially spaced, aligned openings, said flange plate openings being of greater diameter than said base and clamp plate openings, said base plate openings being internally threaded, bolts within said aligned openings and having enlarged heads engaging the outer face of said clamp plate, said base plate around the periphery thereof having a plurality of radially spaced, inwardly extending openings having their axes disposed at substantially right angles to the axes of said aligned openings, said inwardly extending openings being internally threaded and communicating with said extension by means of reduced bores provided in said base plate, set screws within each of said inwardly extending openings being internally threaded and communicating with the inner face of said base plate for supporting one end of the core and means for supporting the other end of the core.

6. A device for supporting a core upon a shaft comprising a hub secured to the shaft, a flange plate secured to the inner end of said hub, an angular extension on the inner face of said flange plate, a base plate having a central opening receiving said extension therethrough in freely spaced relationship and lying flush with the inner face of said flange plate, a clamp plate having a central opening receiving said hub therethrough in freely spaced relationship and lying flush with the outer face of said flange plate, said flange, base and clamp plates having radially spaced, aligned openings, said flange plate openings being of greater diameter than said base and clamp plate openings, said base plate openings being internally threaded, bolts within said aligned openings and having enlarged heads engaging the outer face of said clamp plate, said base plate around the periphery thereof having a plurality of radially spaced, inwardly extending openings having their axes disposed at substantially right angles to the axes of said aligned openings, said inwardly extending openings being internally threaded and communicating with said extension by means of reduced bores provided in said base plate, set screws within each of said inwardly extending openings, reduced shanks on the inner end of each of said set screws passing through said reduced openings and bearing on said extension, means on the inner face of said base plate for supporting one end of the core and means for supporting the other end of the core.

7. A device for supporting a core upon a shaft comprising a hub secured to the shaft, a flange plate secured to the inner end of said hub, an angular extension on the inner face of said flange plate, a base plate having a central opening receiving said extension therethrough in freely spaced relationship and lying flush with the inner face of said flange plate, a clamp plate having a central opening receiving said hub therethrough in freely spaced relationship and lying flush with the outer face of said flange plate, said flange, base and clamp plates having radially spaced, aligned openings, said flange plate openings being of greater diameter than said base and clamp plate openings, said base plate openings being internally threaded, bolts within said aligned openings and having enlarged heads engaging the outer face of said clamp plate, said base plate around the periphery thereof having a plurality of radially spaced, inwardly extending openings having their axes disposed at substantially right angles to the axes of said aligned openings, said inwardly extending openings being internally threaded and communicating with said extension by means of reduced bores provided in said base plate, set screws within each of said inwardly extending openings, reduced shanks on the inner end of each of said set screws passing through said reduced openings and bearing on said extension, means on the inner face of said base plate for supporting one end of the core and means for supporting the other end of the core comprising a substantially frusto-conical member secured to the inner face of said base plate around the periphery thereof and adapted to be received within the end of the core.

8. A device for supporting a core upon a shaft comprising a hub secured to the shaft, a flange plate secured to the inner end of said hub, an angular extension on the inner face of said flange plate, a base plate having a central opening receiving said extension therethrough in freely spaced relationship and lying flush with the inner face of said flange plate, a clamp plate having a central opening receiving said hub therethrough in freely spaced relationship and lying flush with the outer face of said flange plate, said flange, base and clamp plates having radially spaced, aligned openings, said flange plate openings being of greater diameter than said base and clamp plate openings, said base plate openings being internally threaded, bolts within said aligned openings and having enlarged heads engaging the outer face of said clamp plate, said base plate around the periphery thereof having a plurality of radially spaced, inwardly extending openings having their axes disposed at substantially right angles to the axes of said aligned openings, said inwardly extending openings being internally threaded and communicating with said extension by means of reduced bores provided in said base plate, set screws within each of said inwardly extending openings, reduced shanks on the inner end of each of said set screws passing through said reduced openings and bearing on said extension, means on the inner face of said base plate for supporting one end of the core and means for supporting the other end of the core.

end of the core and means for supporting the other end of the core, said means for supporting one end of the core comprising a substantially frusto-conical member secured to the inner face of said base plate around the periphery thereof and adapted to be received within the end of the core, said means for supporting the other end of said core comprising a hub screw-threaded on to the shaft at the other end of said core, a flange plate connected to the outer end of said hub, and a substantially frusto-conical member secured to the inner face of said flange plate around the periphery thereof, and adapted to be received within the other end of said core.

8. A device for supporting a core upon a shaft comprising a hub secured to the shaft, a flange plate secured to the inner end of said hub, an angular extension on the inner face of said flange plate, a base plate having a central opening receiving said extension therethrough in freely spaced relationship and lying flush with the inner face of said flange plate, a clamp plate having a central opening receiving said hub therethrough in freely spaced relationship and lying flush with the outer face of said flange plate, said flange, base and clamp plates having radially spaced, aligned openings, said flange plate openings being of greater diameter than said base and clamp plate openings, said base plate openings being internally threaded, bolts within said aligned openings and having enlarged heads engaging the outer face of said clamp plate, said base plate around the periphery thereof having a plurality of radially spaced, inwardly extending openings having their axes disposed at substantially right angles to the axes of said aligned openings, said inwardly extending openings being internally threaded and communicating with said extension by means of reduced bores provided in said base plate, set screws within each of said inwardly extending openings, reduced shanks on the inner end of each of said set screws passing through said reduced openings and bearing on said extension, means on the inner face of said base plate for supporting one end of the core and means for supporting the other end of the core, said means for supporting one end of the core comprising a substantially frusto-conical member secured to the inner face of said base plate around the periphery thereof and adapted to be received within the end of the core, said means for supporting the other end of said core comprising a hub screw-threaded on to the shaft at the other end of said core, a flange plate connected to the outer end of said hub, and a substantially frusto-conical member

secured to the inner face of said flange plate around the periphery thereof, and adapted to be received within the other end of said core, said second flange plate having oppositely disposed openings therethrough adapted to receive therewithin the opposite ends of a spanner wrench or the like.

9. A device for supporting a core upon a shaft comprising a hub secured to the shaft, a flange plate secured to the inner end of said hub, an angular extension on the inner face of said flange plate, a base plate having a central opening receiving said extension therethrough in freely spaced relationship and lying flush with the inner face of said flange plate, a clamp plate having a central opening receiving said hub therethrough in freely spaced relationship and lying flush with the outer face of said flange plate, said flange, base and clamp plates having radially spaced, aligned openings, said flange plate openings being of greater diameter than said base and clamp plate openings, said base plate openings being internally threaded, bolts within said aligned openings and having enlarged heads engaging the outer face of said clamp plate, said base plate around the periphery thereof having a plurality of radially spaced, inwardly extending openings having their axes disposed at substantially right angles to the axes of said aligned openings, said inwardly extending openings being internally threaded and communicating with said extension by means of reduced bores provided in said base plate, set screws within each of said inwardly extending openings, reduced shanks on the inner end of each of said set screws passing through said reduced openings and bearing on said extension, means on the inner face of said base plate for supporting one end of the core and means for supporting the other end of the core, said extension being of less width than said hub.
